(57) **CLAIM**

The ornamental design for a side panel for a loud speaker, as shown and described.

DESCRIPTION

FIG. 1 is a perspective view from the front-top-left side of the side panel for a loud speaker showing a first embodiment of our new design;

FIG. 2 is a front view of the design shown in FIG. 1;

FIG. 3 is a perspective view from the front-top-right side of the side panel for a loud speaker showing a second embodiment of our new design; and,

FIG. 4 is a front view of the design shown in FIG. 3.

The broken line showing on the drawing disclosure is for illustrative purposes only and forms no part of the claimed design.
